UNITED STATES PATENT OFFICE

JACK BROWN AND WILLIAM F. REUTER, OF OTOE, NEBRASKA

SICKLE GRINDER

Application filed December 31, 1930, Serial No. 505,785. Renewed August 31, 1932.

This invention relates to sickle grinders and its object is to provide a sickle grinder having a stable support and having means for moving the sickle holding member laterally 5 or toward and away from the grinder.

Another object of the invention is the provision of a hand operated platform for holding the sickle, the platform being slideable to bring various parts of the sickle into 10 contact with the grinder and being also pivotally movable toward or away from the grinder, there being also provided rests for holding the platform in position away from the grinder.

Another object is the provision of a sickle platform which is pivotally connected to a handle with linkage for moving the sickle platform toward and away from the grinder when the handle is raised or lowered.

Having in view these objects and others which will be pointed out in the following description, we will now refer to the drawing, in which

Figure 1 is a view in perspective of the sickle grinder showing the sickle holding members in their rest position with the sickle away from the grinder.

Figure 2 is a view in side elevation of a fragment of the sickle grinder with the parts in the position shown in Figure 1.

Figure 3 is a view in side elevation of the sickle grinder with the parts in intermediate position between the operative grinding position and the rest position.

The frame includes rear legs 10 and front legs 11 and 12 arranged in inverted V-shaped pairs having bearings 13 at their upper ends. The frame is braced by means of two transverse braces 14, a pair of crossed braces 15 and an additional brace 16. The bearings 13 receive the shaft 17 which is provided with a grinder 18 and with a driving pulley 19.

The rod 20 is secured at one of its extremities to the leg 11 as shown in Figure 1. This rod 20 extends across the front of the frame and to a considerable distance beyond the opposite end of the frame. It is provided 50 with a pair of braces 21 extending to two

of the legs, the purpose being to provide a rigid support for the free end of the rod 20. Two collars 22 surround the rod 20 and they are freely slideable on the rod. One of the collars has secured thereto a rod 23 while the other collar has a similar rod 24 which terminates in a handle portion. Journalled to the rods 23 and 24 is a transverse rod or tube 25.

The bent rod or tube 26 is pivotally secured at the junction of the rods 23 and 25 and it extends first upwardly and rearwardly and then upwardly. The opposite end portion of the rod or tube 25 is bent to provide an arm 27 which projects upwardly and rearwardly. The rod or tube 28 is secured, preferably by welding, to the arms 26 and 27. The free end portion of the bent rod 26 is formed into a clamp, that portion cooperating with a clamping member 29 having a bolt with thumb nut 30 cooperating with the two clamping members. It should be noted that the rod or tube 28 extends laterally in one direction to a considerable distance where it is turned up to provide a similar clamp including a thumb nut and a sickle clamping member having identical construction with the clamping member on the bent rod 26. The structure of the clamp is best shown in Figures 2 and 3. The rod or tube 28 is further provided with an intermediate clamping member as shown in Figure 1, the purpose of this construction being more fully described in the description of the mode of operation of the sickle grinder. The sickle 31 may be clamped in all three clamps as shown in Figure 1 or it may be clamped to the intermediate clamp and to one of the end clamps.

The grinder further includes a number of stops. The stops which function to maintain the parts in the rest position include the stop 32 projecting upwardly and forwardly from the leg 12 and engaging the rod or tube 25 and the stop 33 projecting upwardly from the handle member 24 for engaging the rod or tube 28. The handle 24 is also provided with a stop member 34 for engaging the rod or tube 28 during the

movement of the sickle holding platform into its operative position.

From the foregoing description it is believed that the operation of the sickle grinder will be obvious. The inoperative position or the position at rest is shown in Figures 1 and 2. When the parts are in this position the tube 25 rests on the stop member 32 and the pipe or rod 28 rests on the stop member 33. When it is desired to move the parts to operative position the operator merely grasps the handle 24 and lifts its free end. The movement following the lifting of the handle is a compound movement depending on three factors. There is the positive thrust through the arms 26 and 27 on the part 28 of the sickle carrying frame. This thrust is in an upward and forward direction but it is partly counteracted by the tension of the spring 35. The first effect of the movement is obviously to remove the pivoted frame from the support 32. The upward and forward action of the members 26 and 27 as partly counteracted by the spring 35 will cause the part 28 to swing over until it rests on the upper extremity of the stop member 34. While this movement is mainly the result of the action of the spring 35 together with the thrust from the parts 26 and 27, the shifting center of mass of the sickle carrying frame also affects the movement whereby the transverse portion 28 is seated on the stop member 34. As soon as the stop member 34 engages the member 28, continued upward movement of the free end of the lever 24 has the effect of positively forcing the sickle carrying frame forward toward the grinder.

During the grinding of the sickle the operator maintains his grasp on the handle 24 in order to control the pressure of the sickle against the grinder. The stop member 34 acts positively so that considerable pressure is possible through the leverage of the lever 24. When this pressure is too great for the best results the operator merely applies less leverage to the handle and the spring 35 then makes the regulation of the pressure extremely sensitive so that it is possible to maintain even the very slightest pressure of the sickle against the grinder. The spring 35 has the further advantage in acting as a buffer to counteract the vibration which might otherwise grind the sickles very unevenly. By maintaining only a slight pressure of the sickles on the grinder, the spring 35 is permitted to compensate for the vibrations in pressure due to the vibrations of the machine. At the same time the stop 34 will prevent the sickle holding frame from jumping entirely away from the sickle as the result of possible severe vibrations.

The sliding collars 22 make it possible to move the sickle 31 to bring consecutive teeth into contact with the grinder 18. The three clamps prevent vibration in the sickle itself

whereas two clamps alone have been found to cause excessive vibration in the sickle itself. The primary purpose of the three clamps, however, is to make it possible to bring the end teeth of the sickle into contact with the grinder and at the same time to provide at least two clamps for holding the sickle. The shifting of the sickle laterally is accomplished through the lever 24.

While we have described our invention in great detail, it is obvious that numerous changes may be made without departing from the spirit of our invention. We therefore reserve to ourselves the rights to all improvements and variations falling within the scope of the appended claims.

Having thus described our invention in such full, clear, and exact terms that its construction and operation will be readily understood by others skilled in the art to which it pertains, what we claim as new and desire to secure by Letters Patent of the United States is:

1. In a sickle grinder, a main frame having a grinder shaft journalled thereon, a support on said main frame positioned in parallelism with said grinder shaft, a frame pivotally and slidably secured to said support, a sickle carrying frame pivotally connected to said pivoted frame, said sickle carrying frame being provided with clamps for securing a sickle thereto, a handle projecting from said pivoted frame, stops on said main frame and on said handle for maintaining said sickle carrying frame in inoperative position, and an additional stop on said handle for engaging said sickle carrying frame when raising said handle to operatively position said sickle carrying frame.

2. In a sickle grinder, a main frame having a grinder shaft journalled thereon, a support on said main frame positioned in parallelism with said grinder shaft, a frame pivotally and slidably secured to said support, a sickle carrying frame pivotally connected to said pivoted frame, said sickle carrying frame being provided with clamps for securing a sickle thereto, a handle projecting from said pivoted frame, a pair of spaced stops on said handle for engaging said sickle carrying frame, one of said stops being adapted to support said sickle carrying frame in its inoperative position and the other of said stops being adapted to engage said sickle carrying frame during the lifting movement of said handle.

3. In a sickle grinder, a main frame having a grinder shaft journalled thereon, a support on said main frame positioned in parallelism with said grinder shaft, a frame pivotally and slidably secured to said support, a sickle carrying frame pivotally connected to said pivoted frame, said sickle carrying frame being provided with clamps for securing a sickle thereto, a handle projecting from

said pivoted frame, and a pair of spaced stops on said handle for engaging said sickle carrying frame, one of said stops being adapted to support said sickle carrying frame in its inoperative position and the other of said stops being adapted to engage said sickle carrying frame during the lifting movement of said handle, and a helical spring secured to said sickle carrying frame 10 and to said handle for facilitating the movement of said sickle carrying frame from either of said stops to the other of said stops.

In testimony whereof we affix our signatures.

15 JACK BROWN.
